Primary Examiner — Kevin K Rudzinski*Assistant Examiner* — Richard Kearney(74) *Attorney, Agent, or Firm* — Charmasson, Buchaca & Leach, LLP(57) **CLAIM**

The ornamental design for a wallet clip, as shown and described.

DESCRIPTION

FIG. 1 is a front elevation view of a wallet clip showing our new design;

FIG. 2 is a cross sectional view taken along line 2-2 of FIG. 1;

FIG. 3 is a top plan view of the wallet clip of FIG. 1;

FIG. 4 is a bottom plan view thereof;

FIG. 5 is a back elevation view thereof; and,

FIG. 6 is a right side elevation view thereof, the left side elevation view being a mirror image thereof.

Broken lines are used to indicate environment and form no part of the claimed design.

Shading lines are used to show solid structures and are not intended to indicate surface decoration.

1 Claim, 1 Drawing Sheet
